UNITED STATES PATENT OFFICE.

AUGUSTUS F. THOMPSON, OF HUNTINGTON, WEST VIRGINIA.

GAS BURNER.

Application filed June 11, 1925. Serial No. 36,401.

To all whom it may concern:

Be it known that I, AUGUSTUS F. THOMPSON, a citizen of the United States of America, and a resident of Huntington, county of Cabell, and State of West Virginia, have invented certain new and useful Improvements in Gas Burners, of which the following is a full and clear specification.

This invention relates to that type of gas-burner in which a jet of gas under pressure is injected into an inlet-tube, preferably of the Venturi type, in such manner as to draw into the inlet-tube a quantity of air, the air and the gas being injected into a mixing-chamber where they are intimately mixed before exit at the burner-tips, and the object of the present invention is to simplify the construction of the mixing-chamber and so construct it that a thorough and even admixture of the gas and air is obtained before the mixture is delivered at the burner-tubes, as more fully hereinafter set forth.

In the drawing—

Fig. 1 is a perspective view of the burner mixing-chamber, minus the gas-supply tube and the burner-tips;

Fig. 2 is a vertical sectional view on the line 2—2 of Fig. 1;

Fig. 3 is a sectional view on the line 3—3 of Fig. 1;

Fig. 4 is a horizontal sectional view taken through the main part of the mixing-chamber;

Figs. 5, 6, 7 and 8 are detail views of a slightly modified arrangement of the mixing-chamber.

Referring to the drawing annexed by reference-characters, 10 designates an inlet cup or bell having in its center a tubular support 11 for the exit-end of the gas-supply pipe, not shown, which is positioned to throw a continuous jet of gas into the inlet-tube 12 connected with the mouth-piece 10. The inner end of this inlet-tube opens upwardly into a tube 13, about midway the length of the same. The tube 13 is provided with a V-shaped deflector 14 which dips

down toward, and to a point near, the exit of the inlet-tube; this double deflector 14 serves to divide the incoming gas and air 50 equally between the two parts of the mixing-tube 13. A parallel mixing-tube 15 is provided and the ends of this tube 15 are connected to the respective ends of the tube 13 by end-connections 16, these end-connections being curved, i. e., semi-circular, to insure easy and even delivery of the mixture into the final mixing-tube 15. The top face of the final tube 15 is provided with a series of openings 17 for the reception of the 60 burner-tips, shown in dotted lines in Fig. 2 at 18, which are desirably of the usual lava type. The whole structure is desirably cast in one piece, the inlet-tube 12 being integral with the under wall of the preliminary mixing-tube 13. This structure provides a very simple way of thoroughly mixing the gas and air, without lowering its pressure at the burner-tips, and at the same time insuring a uniform pressure at the burner-tips, this 70 latter being obviously a very desirable result.

The type of device shown in Figs. 1 to 4 is desirable for use in stoves, where vertical space is limited. In other cases, where vertical space is available, I may use the type 75 illustrated in Figs. 5 to 8, inclusive. In this structure, the arrangement is the same except that the two tubes 13 and 15 are arranged one above the other.

What I claim as new is:

In a burner of the type set forth, an elongated elliptical mixing-chamber consisting of two parallel tubes joined at their ends by curved connections, one of the tubes being provided with a series of burner-tip-holes 85 along its length and the other tube being provided with a gas-and-air inlet midway of its length, a gas-and-air injector connected with said inlet, the tube wall opposite said inlet being extended inwardly to form a 90 double deflector, for the purpose set forth.

In testimony whereof I hereunto affix my signature.

AUGUSTUS F. THOMPSON.
